TUBE CUTTER

Filed Oct. 2, 1946

UNITED STATES PATENT OFFICE

2,448,578

TUBE CUTTER

Ernest E. Condon, Hermanville, Md.

Application October 2, 1946, Serial No. 700,658

7 Claims. (Cl. 30—95)

1

This invention relates to a cutter for cutting tubes, pipes, rods, wire or the like, and has for its object the provision of a device of the character described, which can be applied to the work without adjustment—the device being self-centering.

Another object is to provide a cutter in which the knives are easily removable.

Another object is to provide a tube cutter that will cut tubes without burring, leaving the inside wall of the tube smooth and without grooving or deforming the tube.

Another object is to provide a cutter in which the knives are individually spring-pressed, thereby insuring proper and uniform tension on same throughout the cutting operation.

A further object is to provide a cutter that can be operated by one hand.

Other objects and advantages will appear from the following specification taken with the accompanying drawings where by way of illustration, a preferred embodiment of the invention is disclosed. It will be understood, however, that changes and modifications can be made in the construction of this invention, which is therefore defined by the appended claims.

While this improved cutter can be made for use with pipes, tubes, rods or wire of any size, the embodiment herein described is particularly suited for articles of small diameter and particularly for use in cutting copper tubing as commonly used in automobiles and refrigeration devices. This embodiment is well suited for use by installers and repair men who desire a small, rugged portable cutter that will accommodate all sizes of small tubing etc., say 1 inch and less O. D. The following specification discloses such a device.

In the accompanying drawings:

Fig. 1 is an elevational view of the front side of a cutter embodying the invention.

Fig. 2 is an elevational view of the rear side of cutter Fig. 1.

Fig. 3 is an elevational view of the cutter Figs. 1 and 2 with the jaw open.

Fig. 4 is a sectional view of the cutter Fig. 1 on the line 4—4 of Fig. 1.

Fig. 5 is a sectional view on the line 5—5 of Fig. 1.

Referring to Fig. 1, the numeral 10 denotes a member forming about two-thirds of the body of the device and having a web portion 11 to which the jaw 12 is hinged by pin 13. The ring-shaped body of the device is thus comprised of the portion 10 and the jaw 12, and these parts where the jaw is closed define an opening 14, the axis of which is transverse the plane of the body.

The jaw 12 has a slot in its periphery 15 to receive a catch 16 movably secured in the slot by pin 17. The catch has an opening 18 under

2

one end and a pin 19 at the other end, said pin engaging a hole 20 in the member 10.

The catch has a web 21 which fits into a slot 22 in the jaw. The catch has an outwardly extending portion 23, which, when pressed, inwardly moves the catch to withdraw pin 19 from hole 20 to permit the jaw to be moved to open position as shown in Fig. 3 in a manner that will be obvious.

10 Any suitable locking means for the jaw can be used instead of the foregoing.

The body supports a plurality of spring-pressed rollers and knives. In the drawings three sets of rollers and knives are shown and only one set will be described in detail as all are alike.

15 Referring to Fig. 4, the numeral 24 denotes a bore extending radially through the body of the device. This bore is slightly enlarged at its outer end, and internally threaded as shown at 25.

20 Positioned in bores 24 are the hollow plungers 26 the inner ends 27 of which extend into the opening 14. These inner ends terminate in lugs 28 which are drilled to accommodate the transverse shafts 29 supporting rollers 30, 31 which 25 turn with said shafts, or the rollers may be supported in any other manner on the lugs 28. The outer faces of the rollers are aligned and the rollers are long enough to present ample surface to the tube or other object 32 which is held by 30 all the rollers while being cut as presently described.

The hollow plungers 26 have slots 33 therein, extending longitudinally of the plungers, and adapted to receive pins 34 secured to plates 35 35 which are attached to the body by screws 36. The pins 34 pass through holes 37 in the body.

It will now be seen that the plungers 26 are free to slide or reciprocate in the bores 24, but are prevented from falling out of the body by reason of the pins 34; and that the rollers 30, 31 are revolvably mounted on and move with the plungers. Each plunger 26 is provided with a second plunger 38. Each plunger 38 has a spring 39 at its upper end tending to urge the plungers 38 towards the axis of opening 14. A cap 40 threadedly engaging the outer end of each plunger 26 holds the inner plungers 38 and springs 39 therein. The walls of plungers 26 have slots 41 therein to receive pins 42 connected to 50 plungers 38.

Removably secured to the outer end of each pin 38 is a knife 43 having a slot 44 to permit the knives to reciprocate about the necks 45 of the shafts 29 for the rollers.

55 A screw and washer 46 overlies each knife and the adjustment is such that each knife is free to slide between this washer and the outer end faces of rollers 30.

The knives 43 may have any suitable cutting 60 edges or points such as the points shown at 47,

which, when brought against the object 32 to be cut, will cut clean with a minimum of turning effort.

A spring 48 is placed over the plunger assembly and is held against cap 40 thereof by a cap 49 engaging the threads 25 in the body.

To use the device, the jaw 12 is opened as shown in Fig. 3 and the object to be cut such as the tube 32 is placed against the rollers in the plunger assemblies secured to the member 10 of the body. The jaw is now closed so all three of the plunger assemblies are free to move radially in respect to the axis of the tube 32, the tube will be automatically centered in the device as shown in Figs. 1 and 2 wherein is shown a flanged tube with the flange toward the observer in Fig. 1.

The rollers 30 and 31 will now all be in engagement with the outer wall of the tube as shown in Figs. 1, 2 and 4, and the points 47 of the knives will be resting upon the outer surface of the tube. The rollers 30, 31 will be held against the tube by the springs 48 and the knives will be held against the tube by the springs 39.

Now, if the cutter is rotated about the tube 32, the points of the knives will be forced into the wall of the tube which will be cut thereby. This cutting will be at uniform pressure and is predetermined by the initial setting of the springs 39 which may be adjusted by moving the cap unit 40 up or down in the upper threaded end of the plunger 28. As the tube is cut, the knives 42 are gradually forced inwardly through the wall of the tube toward the axis thereof until the tube is severed.

It will be seen from the foregoing that not only is the object to be cut automatically centered in the device, but even if for a turn or two the object was not so centered, that the turning of the device quickly causes such centering to take place and that at no time can there be uneven feeding of the knives. Thus the difficulties inherent in devices where the knives must be manually fed to the work as the cutter is revolved, are eliminated.

What is claimed is:

1. A cutter comprising a body having an opening therein, a plurality of spring-pressed plungers supported on said body, each of said plungers having a tube-engaging roller at its inner end lying within said opening, and a spring-pressed knife mounted on each of said plungers having an edge adapted to engage the wall of a tube held between said rollers and extending transversely through said opening, whereby upon relative rotation of said cutter and tube, the tube may be cut by said knives.

2. A cutter as claimed in claim 1 wherein the body has a hinged portion on which one of said plungers is mounted to permit said hinged portion to swing away from the remainder of the body to allow a tube to be placed in the opening in the body and said hinged portion closed to cause said tube to be centered and held within said opening by the conjoint action of said plungers.

3. A cutter as claimed in claim 1 wherein said body is ring-shaped and has a hinged arcuate section carrying one of said plungers and adapted to be moved to open said ring to permit the insertion of a tube transversely therein, and locking means for securing said arcuate section in closed position and thereby holding said tube in position to be cut by said cutters.

4. A cutter comprising a body having a central opening and a plurality of bores in said body ex-

tending radially from said opening and perpendicular to the axis thereof, a plunger slidably mounted within each of said bores and extending into said opening, and having a slotted wall, a spring for each of said plungers tending to urge same inwardly toward the axis of said opening, a second plunger slidably mounted within each of said first plungers, a spring for each of said second plungers tending to urge same inwardly toward the axis of said opening, a pin connected to each of said second plungers and extending outwardly through said slots in the walls of said first plungers, and a knife carried by each of said pins and having a cutting edge extending into said central opening beyond the ends of said first plungers therein.

5. A cutter comprising a body having a central opening therein and a plurality of bores in said body extending radially from said opening and perpendicular to the axis thereof, a hollow cap for each of said bores in threaded connection with said body and extending outwardly therefrom, a tubular plunger in each of said bores having a slotted wall and having its inner end extending into the central opening in said body, springs within said caps tending to urge said plungers inwardly, pins supported on said body and extending inwardly into said slots in the walls of said tubular plungers to limit the movement of said plungers in said bores, a second plunger and a compression spring therefor inside each of said tubular plungers, and means extending through slots in the walls of said tubular plungers and connected to said second plungers for movably supporting said knives.

6. A cutter comprising a body having a central opening through the plane of the body and a plurality of bores extending through said body and communicating with said opening therein, a plunger in each of said bores, each of said plungers having a roller having its axis parallel to the axis of said opening, a spring for each of said plungers tending to urge same toward the axis of said opening, means to prevent rotary movement of said plungers as they slide in said bores, knives carried by said plungers, said knives projecting inwardly toward the axis of said opening and beyond said rollers, said knives being yieldably mounted for motion parallel to said plungers, and a spring connected to each of said knives and tending to urge same toward the axis of said opening, whereby a tube centered between said rollers may be cut by said spring-pressed knives.

7. In a cutter, a body having an opening therein, tube-engaging rollers in said opening, means on said body for yieldably holding said rollers in engagement with a body to be cut when located between said rollers and extending through said opening, and spring-pressed knives carried on said means, said knives adapted to engage a tube to cut through same as said knives are revolved about said tube by rotating said body thereabout.
